UNITED STATES PATENT OFFICE

WARD F. HERST, OF GRAND RAPIDS, MICHIGAN, ASSIGNOR TO WOLVERINE BRASS WORKS, OF GRAND RAPIDS, MICHIGAN, A CORPORATION OF MICHIGAN

SEWER-CLEANING IMPLEMENT

Application filed April 2, 1931. Serial No. 527,132.

The present invention relates to sewer-cleaning implements; and its object, generally, is to provide in combination with the long flexible headed rod usually employed for cleaning sewers, drain pipes and the like, an improved device adapted to be clamped on the rod and having a lever handle for moving the rod longitudinally in the sewer or pipe.

This and other and more specific objects hereinafter appearing are attained by, and the invention finds preferable embodiment in, the device particularly described in the body of this specification and illustrated by the accompanying drawing, in which:

15 Figure 1 is a view in perspective of a device adapted to be clamped on a sewer-cleaning rod for operatively moving the same in its longitudinal direction;

20 Figure 2 is a side view of said device and an edgewise view of the rod, partially sectioned on line 2—2 of Figure 3;

Figure 3 is a sectional view of the same taken on line 3—3 of Figure 2;

25 Figure 4 is a side view of the inner portion of the lever handle of said device; and

Figure 5 is a view in perspective of a clamp shoe thereof.

In this drawing is shown a long flat flexible rod 1 provided at one end with a cleaner head 2 of common form employed for cleaning sewers, drain pipes and the like, and a device designated generally 3 clamped in various positions along the rod for moving the same longitudinally in the sewer.

35 This device 3 is hollow (i. e. the rod 1 passes through it) one flat side 4 of the rod, except when clamped as hereinafter described bearing slidably on the inner surface 5 of the bottom 6 of the device, and the device's sides 7 extending around the opposite edges 8 of the rod.

A lever 9 is fulcrumed on a pivot pin 10 mounted on said sides 7 and extending through their openings 11, which pin may 45 have the head 12 and the thumb nut 13 on its

threaded opposite end 14, so that the parts of said device may be readily assembled and disassembled. This lever's outer end forms a handle 15 and its inner end a cam, or (as illustrated by the drawing) a pair of cams 16, 50 17 on the opposite sides respectively of a line *a—a* extending in the lever's longitudinal direction and through the pivot pin, the low point 18 of both cams being intersected by said line and the high points 16¹ and 17¹ 55 of the cams 16, 17 respectively being remote from said line and on the opposite sides thereof.

A clamp shoe 19 in the hollow device 3 has a middle or body portion 20 extending 60 between the rod 1 and the inner end of the lever, and opposite sides 21 provided with outwardly extending slots or bearings 22 through which the pivot pin 10 passes, and bears slidably in the movement of the shoe 65 toward or from the bottom 6 of the device. It will be seen that when the lever is turned to the position seen in Figures 1 and 2, the cam 17 is turned into operative engagement with the shoe to clamp the rod between the shoe 70 and said bottom 6, and that the same manual movement which thus turns the lever operates to draw the rod toward the right hand side of Figure 2; and that when the lever is turned to its opposite position the other cam 16 75 engages the shoe and the rod is moved toward the left hand side of Figure 2; and that when the lever is turned to an intermediate position the rod is released and the device may be slid freely therealong to a desired new position to be clamped on the rod. 80

It will also be seen that the lever, the pivot pin, the shoe and the body 3 itself of the device are all held in cooperating position by a single part, the nut 13. 85

I claim:

A handle for operating an elongated tool comprising: a hollow member having a bottom on whose inner surface the tool bears 90 slidably in its longitudinal direction, and

sides extending around the opposite edges of the tool; a pivot pin mounted on said sides; a lever fulcrumed on the pivot pin, and having a cam inner end and an outer end handle portion, said lever being turnable to a position wherein its inner end clamps the tool on said bottom so that the tool may be moved longitudinally by the lever turned to its said position; a clamp shoe having a middle portion extending between the tool and the inner end of the lever, and sides provided with outwardly extending bearings in which the pivot pin slidably bears.

In testimony whereof I have hereunto set my hand at Grand Rapids, Michigan this 30th day of March, 1931.

WARD F. HERST.
